The ornamental design for fog machine, as shown and described.

DESCRIPTION

FIG. 1 is a front, right, and top perspective view of a fog machine, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged detail view of area 9 circumscribed within FIG. 1.

Evenly spaced broken lines and unshaded areas depict portions of the fog machine that form no part of the claimed design. Dot dash dot broken lines in the drawings denoting the boundaries of the detail areas form no part of the claim. The broken lines shown in the drawings are included for the purpose of illustrating portions of the fog machine that form no part of the claimed design.
